(57) **CLAIM**

The ornamental design for a headset as shown and described.

DESCRIPTION

FIG. 1 is a front perspective view of a headset showing our new design;

FIG. 2 is a bottom perspective view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a right-side elevation view thereof; and,

FIG. 8 is a left-side elevation view thereof.

The broken lines on the side of the headband of the headset represent an ornamental line that form no part of the claimed design. The broken lines immediately adjacent the shaded areas represent the bounds of the claimed design while all other broken lines are directed to unclaimed features that form no part of the claimed design.
